WINDING MACHINE

Robert Pash, Cranford, N. J., assignor to Western Electric Company, Incorporated, New York, N. Y., a corporation of New York

Application September 28, 1932, Serial No. 635,178

9 Claims. (Cl. 242—4)

This invention relates to winding machines and more particularly to machines for winding coils upon cores which have a central space through which the turns of a coil pass. 5 Such cores may be for example, doughnut shaped, horseshoe shaped, triangular, etc., their characteristic feature being the partial or complete enclosure by the axially curved or bent core thereof of a space through which the windings 10 of a coil on the core must pass. For the purposes of this disclosure the word "toroidal" will be used hereinafter as the name for such coils and their cores and to include not only such structures as have a complete annulus for core but also those 15 which may be considered as parts of such.

A primary object of this invention is to provide a toroidal coil winding machine wherein coils may be wound upon toroidal cores with great facility at a high speed, with the strand being wound 20 upon the core under substantially constant tension. In the embodiment here disclosed the invention provides means to drive the guide ring with predeterminedly cyclically varying rotational velocity to compensate for the cyclical 25 variation in the length of wire between the guide and the core and thus permit the spool ring to travel or be driven at an unvarying rate.

In one embodiment of this invention as applied to a machine for winding the closed ring core 30 toroidal coils used for loading telephone circuits, there is provided a guide ring to take the wire to be wound on the core from a spool ring and carry the wire around the core. The guide ring and the spool ring are themselves incomplete 35 annuli with a gap in each to permit them to pass over the core when the latter is positioned for winding and over the completed coil when it is removed. In operation the guide ring and spool ring, which are interlinked with the toroidal core, 40 move in a closed path passing through the space enclosed or partially enclosed by the core which in turn extends through the space inside of the guide ring and spool ring. Separate and independent means are provided to drive the guide ring with a predetermined cyclically irregular motion and to allow the spool ring, propelled 45 primarily by the withdrawal of wire therefrom, to float at a substantially constant rate of rotation so that the guide ring runs alternately faster and 50 slower than the spool ring during each rotation thereof. This action compensates for the cyclically varying distance and direction of the strand guide on the guide ring from the momentary point of application of the strand to the core, and helps 55 to keep the tension under which the wire is trans-

ferred constant. To assist further in imposing, maintaining and regulating this tension of the wire, means are provided to apply an adjustable drag or braking effect to the spool ring.

Other objects and advantages of this invention 5 will appear more fully from the following detailed description taken in connection with the accompanying drawings, wherein

Fig. 1 is a view in horizontal longitudinal section through the principal axis of a winding machine embodying the features of this invention; 10

Fig. 2 is a view in transverse vertical section taken on the line 2—2 of Fig. 1;

Fig. 3 is a view in right hand end elevation of the machine with a portion of the top broken 15 away;

Fig. 13 is an enlarged broken detached radial 45 plan view of a portion of the guide ring showing the strand guide member and the strand guide sheave thereof.

Referring now to the drawings in detail wherein like reference numerals indicate similar parts throughout the several views, the winding machine in the embodiment disclosed comprises a 50 housing and mounting casing generally indicated by the numeral 20.

A drive shaft 21 mounted in the housing and provided with a driven gear 22 and a driving gear 23 conveys power from a motor 24 of any ap- 55

proved kind to a main driving gear 25. A group of three planetary gears 26 is mounted upon the main gear 25 upon shafts 27 journaled, as shown in Fig. 1, at their left hand ends in anti-friction bearings 28 carried by the gear 25 and at their right hand ends in similar bearings 29 carried by an annular support 30 attached to the gear 25 by means of screw bolts 31 entering bosses 32 found upon the gear 25. The gear 25 is further formed 10 with an integral axial sleeve 33 extending outwardly to the right by means of which the gear 25 is mounted with freedom of rotation thereon upon a main drive shaft 34. The shaft 34 is carried in bearings 35 and 36 to be described 15 later.

A collar 37 is mounted upon and keyed to the outer surface of the sleeve 33. This collar is formed at its right hand end with clutch teeth which engage with corresponding teeth formed 20 upon a collar 38 mounted upon the shaft 34 with freedom to slide thereon but keyed thereto to rotate therewith. The collar 38 is formed with a conical brake surface 39 adapted when the collar 38 is forced to the right to engage with a complementary surface 40 formed on a part of the casing 20 and thereby lock the shaft 34 against rotation. The collar 38 is normally held in engagement with the collar 37 by a spring 41 abutting at one end against the collar 38 and at the 25 other end against an annular shoulder 42 formed upon the shaft 34. Further details of this clutch mechanism are not pertinent to the invention as any mechanism having the same function can be substituted therefor. Suffice it to say that means 30 are provided to operate the clutch from outside the casing 20.

A gear 43 is mounted upon the outer surface of the collar 37 with freedom to rotate thereon. Gear 43 is formed with an integral leftwardly extending axial sleeve formed at its extremity with gear teeth which mesh with a second group of three planetary gears 44 also mounted upon the same shafts 27 as the first group of planetary gears 26.

A third group of three transmission gears 45 is mounted upon the gear 25 on shafts 46 journaled similarly to the shafts 27 in the gear 25 and support 30. These transmission gears 45 mesh respectively with the gears 26 to be driven 50 thereby. An internally toothed balance ring 47 meshes with and floats upon all the gears 45 for a purpose to be described later.

The first group of planetary gears 26 also meshes with teeth formed on an enlarged head 55 48 formed on a shaft 49 journaled in anti-friction bearings mounted in a portion of the casing 20.

The bearing 35, above referred to, for the left hand end of the shaft 34 is positioned in the right hand face of the head 48 and concentric therewith. The two shafts 34 and 49, however, have no other direct relation or connection. A head 50 rigidly mounted on the left hand extremity of the shaft 49 is formed with a concentric outwardly facing brake drum surface 51. Around 60 the brake drum surface 51 is positioned with frictional contact therewith a brake band member 52 preferably as disclosed a plurality of intercontinuous turns of wire having a square cross-section. The right hand end of this square wire 52 70 is detachably attached by any convenient means (not shown) to the casing 20 or other stationary element of the machine such as a detachable auxiliary casing 53 over the braking device now being described and detachably mounted on the 75 main casing 20.

The left hand end of the brake band 52 is detachably attached by any approved means to an adjusting member 54 in the shape of a single headed drum integral with or secured to a shaft 55 rotatably mounted in a stub sleeve 56 formed on the housing 53. On the outer surface of the sleeve 56 is rotatably mounted a tensioning dial sleeve 57. The cylindrical part of the drum 54 overhangs and surrounds the right hand part of the tensioning sleeve 57 and in the space between these two parts is located a heavy spiral tensioning spring 58 fastened at its one end to the outer surface of the sleeve 57 and at its other end to the inner surface of the drum 54.

At its left hand end the sleeve 57 is provided 15 with a rack gear which engages with a worm 59 mounted in the casing 53 and provided with a hand wheel (not shown). Intermediate its ends the sleeve 57 is provided with a dial collar 61 which may be graduated in any desired units 20 and may be read through a window 62 adjacent thereto in the casing.

Rotation of the worm 59 by means of the hand wheel will rotate the sleeve 57 and thus increase or diminish the tension of the spring 58 tending 25 to turn the drum 54. This in turn tends to tighten or loosen the pressure of the brake band 52 on the brake drum 51, thus increasing or lessening the resistance to rotation which the toothed head 48 offers to the planetary gears 26, 30 and so governing the speed of rotation of the gears 26, the shafts 27, the gears 44 and the gear 43.

The gear 43 meshes with a gear 63 keyed to a shaft 64 journaled in the casing and having keyed 35 thereto a gear 65. Arranged equidistantly around the gear 65 and meshing therewith are five gears 66 each mounted on a corresponding shaft at the other end of which is one of a corresponding group of five partial gears 67. A spool ring 68 surrounds the group of partial gears 67 and is provided on its inner periphery with gear teeth to mesh with the partial gears 67 by which it is carried and driven.

The spool ring 68 is an incomplete circle having 45 a gap to allow a toroidal core to enter the ring to be wound and to be withdrawn therefrom after winding as will be explained hereinafter in more detail. The ring 68 and the partial gears 67 are so proportioned and arranged that whenever 50 the gap in the ring passes over any one of the five partial gears, that part of the partial gear in question which has no teeth will be toward the ring and hence any wire carried in the circumferential spool groove of the ring and drawn 55 across the gap more or less tautly will not be abraded by the teeth of the gear.

On the shaft 34 near its right hand end is mounted a double drive arm 69. A cam link 70 is pivotally coupled at one of its ends to one extremity of the drive arm 69. Intermediate its extremities the cam link 70 carries a cam pin 71 having a cam roller 72 thereon. To the other end of the cam link 70 is pivotally coupled one end of a drive link 73 which in turn is pivotally 65 connected at its other end by means of a pin 74 to a gear 75 mounted on the shaft 34 with freedom to rotate thereon.

In the right hand end of the casing 20 is detachably mounted a cam block 76 having in its 70 inner left hand face a cam track 77 to receive and guide the cam roller 72 and the cam pin 71 of the cam link 70. Identical parts are mounted in similar fashion on the respectively diametrically opposite sides of the gear 75 to counterbalance the 75

cam link 70, the mass of the cam pin 71 and roller 72 and the drive link 73, but are otherwise functionless dummies, the weight which counterbalances the cam pin 71 and the cam roller 72 not entering the cam slot 77.

The gear 75 meshes with a pair of gears 78 keyed to a pair of shafts journalled in the casing 20 on the other end of each of which shafts is mounted a gear 79. A wire winding guide ring 82 surrounds and meshes with the two gears 79, by means of gear teeth cut on the inner periphery of the ring. The ring 82 is further carried by a pair of grooved idler rolls 83 suitably mounted on shafts carried by the casing.

15 The guide ring 82 and the spool ring 68 are each incomplete rings as shown in Figs. 7 and 8, being formed with corresponding gaps to permit of a toroidal core being positioned partly within the rings 68 and 82 for winding a wire upon the core.

20 A clamping device generally indicated by the numeral 84 is mounted directly in front of the rings 68 and 82 to hold a toroidal core 85 in position to be wound. The nature and detailed construction of the clamping device are irrelevant to the present invention and so will not here be described in detail being sufficiently disclosed in Fig. 3 of the drawings. It suffices to note that the device 84 holds a toroidal core 85 clamped therein with the center of the core substantially in the path of motion of the wire guide ring 82, and with the central plane of the toroidal core passing through or near the axis of rotation of the guide ring. Also the device 84 is mounted to be movable to distribute the windings as desired on the core. Movement of the clamping device and core may be by hand, or means may be provided to effect this motion automatically by connection to some moving part of the machine proper, or by an independently controlled separated drive.

40 In the upper part of the housing which covers the drive of the spool ring 68 is mounted a shaft carrying a gear 86 meshing with the main drive gear 25 for driving the machine by hand to adjust the positions of the rings 68 and 82 when the power is shut off. This hand drive gear 86 is actuated by any approved disconnectable hand operated device whose precise nature is not relevant to the invention and hence is not shown.

45 In an upper part of the housing 20 is positioned and mounted a supply spool supporting and driving mechanism generally indicated by the reference numeral 87. Power is carried from the motor 24 through various gears as indicated in Fig. 3 to a gear 88 mounted on a shaft 89 journalled at both ends in the casing 20 near one end of the shaft. A second gear 88, twin to the first, is mounted on the same shaft 89 near the other end thereof so that the shaft 89 and the two gears 88-88 rotate as one. A pair of twin levers 90 is pivotally mounted respectively beside the gears 88 and free to rotate coaxially therewith. On each of the levers 90 is mounted one of a pair of shafts on which is an anti-friction bearing carrying rotatably thereon one of a pair of twin broad-grooved sheaves 91-91. Each of these sheaves 91 meshes with the corresponding gear 88 by means of gear teeth formed on one rim of each sheave 91. Since the levers 90 carrying the toothed sheaves 91 rotate about the same axis as the gears 88 the latter are always in mesh with the sheaves 91 in all positions of the levers 90.

50 Above and in front of the sheaves 91 is positioned a shaft on which is mounted a pair of narrow-grooved sheaves 92 whose center planes are parallel to but outside of the center planes of the

broad-grooved sheaves 91. Above and behind the sheaves 91 is similarly located and supported a pair of narrow-grooved sheaves 93 whose center planes are parallel to and inside of the center planes of the broad-grooved sheaves 91.

5

Around the three sheaves, one each of the pairs 91, 92 and 93, lying approximately in one plane, passes one of a pair of endless belts 94. These belts may be thought of as passing forward over the tops of the sheaves 93, down in front of, under and up behind the sheaves 91 to pass up behind, forward over the sheaves 92, down under the sheaves 91 for the second time and up behind and forward again over the sheaves 93. The twin levers 90 may be tied together by a cross-bar at their outer ends to which a weight may be hung or a spring attached tending to draw the cross-bar down, thus keeping an adjustable downward tension on the movable gear-sheaves 91 to take up the slack of the belts 94.

15

20 A supply spool 95 of ordinary construction having a cylindrical barrel between two disc shaped heads and having a reserve supply of wire to be wound on cores is laid across the belts as shown in Figs. 3 and 4, resting with the wire wound on its barrel lying directly against the belts 94 and the two belts passing just inside of the heads of the spool to hold the same laterally in place. The belts 94 will then turn the spool 95 in such fashion that the peripheral velocity of the outer layer 25 of wire will always be the same as the linear velocity of the belts regardless of the quantity of wire on the barrel of the spool.

25

30 The spool being laid on the belts as shown in Fig. 3 with the wire wound clockwise thereon, and the belts 94 running down at the rear and up at the front of the spool, the wire 96 will be unwound and delivered from the spool at a constant rate dependent only upon the speed of the belts 94. A guide sheave 97 is mounted on the casing above 35 the spool ring 68 to assist in transferring a supply of wire from the reserve supply spool 95 to the spool ring 68 as required.

35

40 Appropriate means of any approved type are interposed between the motor 24 and the spool device drive gear 88 to start and stop the device 87 independently of the rest of the machine and to regulate the speed of the drive gear 88. The nature of these means is not relevant to the invention and so they are not shown.

45

45 A counting device of any approved construction may be mounted on the casing as generally indicated at 98 to record the amount of wire wound on a core. This device 98 is also not shown in detail as it is not pertinent to the invention and such devices are well known and of many forms.

50

55 The spool ring 68, shown in detail in Figs. 10 and 12, is provided with a deep peripheral groove or channel 99 for the reception of a supply of wire to be wound upon a core; and the guide ring 82 is provided with a notched take-off member 100 (Figs. 12 and 13) and a guide sheave 101. The member 100 overhangs the channel 99 of the spool ring to lift a wire out of the channel and the guide sheave 101 guides the wire into place on the core 60 to be wound as the guide ring carries the sheave 101 around the core.

55

65 To describe the operation of the embodiment of the invention here disclosed let it be assumed that all power is shut off, and that a core 85 to be wound with wire is in position in the clamping device 84. A reserve supply spool of wire to be wound on a core is placed in position at 95 on the belts 94 and a sufficient length drawn off by hand to pass over the sheave 97 and be hooked at 70

70

75

its end into the hole 102 in the spool ring 68 to fasten the wire 96 to the spool ring. The clutch device is then operated to force the collar 38 (Fig. 1) to the right to disengage the collar 38 (Fig. 1) to the right to disengage the collar 38 from the sleeve 37 and to engage the complementary brake surfaces 39 and 40 thus locking the guide ring 38 and its driving train of mechanism against rotation.

The motor 24, which is provided with any approved means to start, stop and reverse its motion, is then started in a direction to drive the gear 23 clockwise as seen in Fig. 5, thus driving the main drive gear 25 counter-clockwise. The motion is transmitted through the planetary gears 26 and 44 to the gear 43 and thence through the gear 63 and gears 66 to the five partial gears 67 which support and drive the spool ring 68 in clockwise rotation.

At the same time the motor 24 is coupled to the gear 89 through the intervening transmission means and clutch to rotate the gear 89 clockwise thus driving the belts 94 to unreel the wire 96 from the spool 95 at constant speed.

These parts and their relative rates of motion are so proportioned and arranged that the spool ring 68 will withdraw the wire 96 from the reserve wire supply spool 95 under a constant predetermined tension substantially equal to the tension under which the wire will later be wound upon the core 85.

When a sufficient quantity of wire for the proposed coil on the core 85 has been wound in this way into the channel 99 of the spool ring the motor 24 is stopped and is uncoupled from the reserve supply spool drive gear 89 as this gear 89 and its appurtenant apparatus will not be actuated again until another supply of wire for immediate winding is to be put on the spool ring. The wire is then cut between the guide sheave 97 and the spool ring.

By manual actuation of the gear 86 the spool ring 68 is now moved to bring the gap therein into alignment with the gap in the guide ring 82. The clutch device on the shaft 34 is then operated to disengage the brake surfaces 39 and 40 and to re-engage the sleeve 37 and collar 38 thus releasing the guide ring 82 and its drive and recoupling the latter to the main drive.

The free end of the wire on the spool ring is then brought up over the notched take-off member 100 (Fig. 10), around the guide sheave 101 on the guide ring, and in to the core and fastened thereto.

The motor 24 is then reversed and started to run in the opposite direction to that used in the spool ring filling operation just described. The spool ring is driven by the same sequence of mechanism as before at a substantially unvarying rate of speed in counter-clockwise rotation as seen in Fig. 3. The driving arm 69 (Figs. 1 and 2) is also driven at a substantially constant rate of speed but as it drives the cam pin 71 and cam roller 72 around the fixed cam track 77 the latter enforces a rhythmic opening and closing of the angle between the cam link 70 and the driving link 73 with the result that while the driving arm 69 and the gear 75 make the same number of revolutions per minute, during each revolution the gear 75 alternately runs ahead of and lags behind the unvaryingly moving driving arm 69. This enforced and predetermined cyclic acceleration of the gear 75 is carried on through the gears 78 and 79 to the guide ring 82.

The elements of the spool ring drive and of the guide ring drive are so proportioned and re-

lated that the spool ring and the guide ring make the same relative number of revolutions per minute. The guide ring, however, may alternately run ahead of and lag behind the unvaryingly rotating spool ring during each revolution thereof. In the sum total of their relative motions the guide ring lags behind the spool ring by an amount representing the length of wire unreeled from the spool ring and wound upon the core.

Fig. 7 is a diagrammatic picture of a sequence of positions of the guide sheave 101 as it is carried around a core 85 during the winding operation, and shows the cyclical variation in the length of free wire between the sheave 101 and the core. In some machines heretofore used, the sheave 101 moves in its eccentric orbit about the core 85 at unvarying speed. As the sheave moves down from the center of the core through the lower half of its orbit, it takes wire from the spool ring to wind upon the core plus wire to compensate for the increasing distance between the sheave and the core. As the sheave moves over the upper half of its orbit the lessening distance between the sheave and the core may, in some instances, tend to more than balance the length of wire being wound on the core so that wire is actually being put back on the spool ring while still being wound on the core. The motion of the wire coming off the spool ring is partly an unreeling entailing rotation of the spool ring, and partly an unwinding from and rewinding on the spool ring requiring no relative rotation thereof. Hence, in machines where the guide ring turns at an unvarying rate, the spool ring must alternately run ahead of and lag behind the guide ring. A brake or other adjustable tension device in these prior machines keeps the necessary winding tension upon the wire by exerting a constant yieldingly retarding action on the spool ring. Due to the inertia of the parts when the guide of these machines is taking wire from the spool at an increasing rate during half the winding cycle there is naturally a tendency for the tension in the wire to increase which will be reversed into a tendency to produce slack during the other half of the winding cycle. This is compensated by a more or less complex and delicate system of yieldingly mounted guide sheaves on the guide ring the distance between which varies against spring pressure roughly speaking inversely with the varying take-off of wire from the spool ring.

According to the present invention the spool ring runs at unvarying speed and the guide ring is driven at a cyclically varying speed to compensate for the cyclically varying distance between the guide sheave 101 and the core 85 thus keeping the rate at which wire is unreeled from the spool ring constant and so keeping the tension on the wire constant without any additional compensating means.

There being no yieldingly movable masses associated with the guide ring, it may be given unvarying dynamic balance and can be driven at high speed without centrifugal disturbances. Also, the speed of operation can be materially increased without entailing increasingly accelerated changes in tension of the wire, a matter of much importance when dealing with fine wires.

The brake device including the drum 50 and band 52 are adjusted so that when the machine is running at full speed the shaft 49 and head 48 are held motionless or creep only very slowly thus supplying the resistance to turning of the head 48 which enables the latter to force the

planetary gears 26 to rotate as they are revolved about the head 48 by the gear 25. Evidently this resistance to rotation of the head 48 will not be sufficient, when so adjusted, to withstand the 5 rotary stress on the head 48 involved during the positive and negative accelerations respectively of the moving parts. Hence, the auxiliary gears 45 meshing with the gears 26 and the balance ring 47 floating on the gears 45 are provided. 10 During acceleration the inertia of the ring 47 tends to assist the head 48 in forcing the gears 26 to rotate as they revolve and the ring 47 is so proportioned that this effect, which varies in magnitude and sense with the acceleration, 15 offsets or balances the added accelerative turning stresses on the head 48 and hence prevents the accelerative actions and reactions from disturbing the tension on the wire being wound. Thus the machine can be started and brought 20 up to running speed or brought to a stop under heavy positive or negative acceleration in a very short time without adverse effects on its adjustments or operation. The balance ring 47 further acts as a fly wheel tending to absorb and iron 25 out the pulsating reaction upon the drive of the alternately positively and negatively accelerated gear 75 and its associated parts, and of the cam pin 71.

It will be obvious that the embodiment herein disclosed is only illustrative and not exhaustive of the invention and may be varied in many ways without departing from the spirit of the invention as principally characterized by the provision of means in a winding machine to drive the strand winding guide thereof at a predetermined varying speed and as further characterized by additional features and combinations thereof particularized and pointed out in the appended claims.

What is claimed is:

40 1. In a winding machine, a spool ring, a winding guide independent thereof but coacting therewith, means to drive the winding guide comprising a motor, a driving arm driven by the motor with substantially unvarying motion, a cam link driven by the driving arm, a driving link driven by the cam link to drive the winding guide, and a cam member coacting with the cam link to convert the substantially unvarying motion of the driving arm into cyclically positively and negatively accelerated motion of the driving link.

45 2. In a winding machine, a spool ring, a winding guide independent thereof but coacting therewith, means to drive the winding guide comprising a motor, a driving arm driven by the motor with substantially unvarying motion, a cam link driven by the driving arm, a driving link driven by the cam link to drive the winding guide, and an interchangeable cam member coacting with the cam link to convert the substantially unvarying motion of the driving arm into cyclically positively and negatively accelerated motion of the driving link.

50 3. In a winding machine, strand supply means movable in a circular path, a winding guide movable in a circular path, a principal driven member rotatable at constant speed, means interposed between the driven member and the strand supply means to drive the latter at constant speed, and means independent of the means to drive the supply means interposed between the driven member and the winding guide to drive the latter at a speed having a predetermined cycle of variation.

55 4. In a winding machine, strand supply means

mounted to be movable in a circular path, a winding guide mounted independently of the strand supply means and movable in a circular path, a principal driven member rotatable at constant speed, supply driving means interposed between the member and the strand supply means for driving the latter at constant speed, and guide driving means independent of the supply driving means and interposed between the member and the winding guide to drive the latter at a speed having a predetermined cycle of variation.

5 5. In a winding machine, strand supply means movable in a circular path, a winding guide movable in a circular path, a principal driven member rotatable at constant speed, means interposed between the driven member and the strand supply means to drive the latter at constant speed, means independent of the means to drive the supply means interposed between the driven member and the winding guide to drive the latter at a speed having a predetermined cycle of variation, and adjustable means to alter the constant speed of the supply means.

10 6. In a winding machine, strand supply means movable in a circular path, a winding guide movable in a circular path, a principal driven member rotatable at constant speed, adjustable means interposed between the driven member and the strand supply means to drive the latter at adjustably constant speed, and means independent of the means to drive the supply means interposed between the driven member and the winding guide to drive the latter at a speed having a predetermined cycle of variation.

15 7. In a winding machine, a spool ring mounted for rotation, a guide ring mounted independently of the spool ring for rotation, a principal driven member rotatable at constant speed, power transmission means interposed between the member and the spool ring to drive the latter at constant speed and including an adjustable element to alter the constant speed of the spool ring, and second power transmission means interposed between the member and the guide ring to drive the latter at a speed having a predetermined cycle of variation.

20 8. In a winding machine, a spool ring mounted for rotation, a guide ring mounted independently of the spool ring for rotation, a principal driven member rotatable at constant speed, power transmission means interposed between the member and the spool ring to drive the latter at constant speed and including an adjustable element to alter the constant speed of the spool ring, and second power transmission means interposed between the member and the guide ring to drive the latter at a speed having a predetermined cycle of variation and including an interchangeable element to alter the cycle of variation.

25 9. In a winding machine, a spool ring mounted for rotation, a guide ring mounted independently of the spool ring for rotation, a principal driven member rotatable at constant speed, power transmission means interposed between the member and the spool ring to drive the latter at constant speed, and second power transmission means interposed between the member and the guide ring to drive the latter at a speed having a predetermined cycle of variation and including an interchangeable element to alter the cycle of variation.
